US0D1079714S

(12) **United States Design Patent** (10) Patent No.: **US D1,079,714 S**
(45) Date of Patent: ** Jun. 17, 2025

(54) **DISPLAY SCREEN OR PORTION THEREOF WITH GRAPHICAL USER INTERFACE**

(71) Applicant: **Typewise AG**, Binningen (CH)

(72) Inventors: **Janis Berneker**, Zürich (CH); **David Eberle**, Basel (CH)

(73) Assignee: **Typewise AG**, Binningen (CH)

(**) Term: **15 Years**

(21) Appl. No.: **29/825,777**

(22) Filed: **Feb. 4, 2022**

(30) **Foreign Application Priority Data**

Aug. 10, 2021 (WO) WIPO107596

(51) **LOC (15) Cl.** **14-04**

(52) **U.S. Cl.**

USPC **D14/486**

(57) **CLAIM**

The ornamental design for a display screen or portion thereof with graphical user interface, as shown and described.

DESCRIPTION

The FIGURE is a front view of a display screen or portion thereof with graphical user interface according to the present invention.

The broken line rectangle shows the display screen or portion thereof and forms no part of the claimed design. All other broken lines show features of the graphical user interface and form no part of the claimed design.

1 Claim, 1 Drawing Sheet
